UNITED STATES PATENT OFFICE.

PAULINE CALDWELL LOCKE, OF BIRMINGHAM, ALABAMA.

DESIGN FOR A FLOWER HOLDER FOR CHURCHES.

Application filed September 10, 1925. Serial No. 14,749. Term of patent 7 years.

To all whom it may concern:

Be it known that I, PAULINE CALDWELL LOCKE, a citizen of the United States of America, residing at Birmingham, in the county of Jefferson and State of Alabama, have invented a new, original, and ornamental Design for Flower Holders for Churches, of which the following is a specification, reference being had to the accompanying drawing, forming part thereof.

I claim:

The ornamental design for a flower holder for churches, as shown.

PAULINE CALDWELL LOCKE.
